Primary Examiner—Martie K. Holtje*Attorney, Agent, or Firm*—Cesari and McKenna, LLP[57] **CLAIM**

The ornamental design for a bookmark with attached fold-out pen, substantially as shown.

DESCRIPTION

FIG. 1 is an isometric view from the front of a bookmark with attached fold-out pen incorporating the design, and with the pen in the folded position;
FIG. 2 is a right-side view thereof;
FIG. 3 is a left-side view thereof;
FIG. 4 is a front view thereof; and
FIG. 5 is a rear view thereof;
FIG. 6 is a bottom plan view thereof;
FIG. 7 is a top plan view thereof; and,
FIG. 8 is an isometric view illustrating the pen in the unfolded position.
